(57) **CLAIM**

The ornamental design for an armored assault vehicle, as shown and described.

DESCRIPTION

A portion of the disclosure of this design patent document contains material, which is subject to copyright protection. The copyright owner has no objection to the facsimile reproduction by anyone of the patent document or the patent disclosure, as it appears in the U.S. Patent and Trademark Office patent files or records, but otherwise reserves all rights under the copyright laws of the United States.

FIG. 1 is a perspective view of an armored assault vehicle, in accordance with the present invention.

FIG. 2 is a top view of an armored assault vehicle, in accordance with the present invention.

FIG. 3 is a bottom view of an armored assault, in accordance with the present invention.

FIG. 4 is a right lateral view of an armored assault vehicle, in accordance with the present invention.

FIG. 5 is a left lateral view of an armored assault vehicle, in accordance with the present invention.

FIG. 6 is a front view of an armored assault vehicle, in accordance with the present invention; and,

FIG. 7 is a rear view of an armored assault vehicle, in accordance with the present invention.

The broken lines showing the environment in the Figures are for illustrative purposes only and form no part of the claimed design.
